(57) **CLAIM**

The ornamental design for a set of grips for game controller, as shown and described.

DESCRIPTION

FIG. 1 is a front view of a set of grips for game controller showing my new design;

FIG. 2 is a left view thereof;

FIG. 3 is a right view thereof;

FIG. 4 is a top view thereof;

FIG. 5 is a bottom view thereof;

FIG. 6 is a front and bottom perspective view thereof;

FIG. 7 is a front, right and bottom perspective view thereof; and,

FIG. 8 is a front, left and top perspective view thereof.

The broken lines shown in the figures are for the purpose of illustrating portions of the set of grips for game controller that forms no part of the claimed design. The unshaded areas between solid and broken lines form no part of the claimed design.
